(57) **CLAIM**

The ornamental design for a car brake/clutch pedal, as shown and described.

DESCRIPTION

FIG. 1 is a perspective view of the car brake/clutch pedal according to the present invention;

FIG. 2 is a front elevational view thereof;

FIG. 3 is a rear elevational view thereof;

FIG. 4 is a bottom view thereof;

FIG. 5 is a top view thereof;

FIG. 6 is a side view thereof; and,

FIG. 7 is an opposite side view thereof.

The broken line showing the location of apertures is for purposes of illustrating environment and forms no part of the claimed design.
